DISPLAY MOLDING UNIT FOR STORE FIXTURES OR THE LIKE

Glen E. Linscott, Grand Rapids, Mich., assignor to The Bulman Corporation, Grand Rapids, Mich., a corporation of Michigan

Application October 16, 1958, Serial No. 53,001

Term of patent 3½ years

(Cl. D1—3)

Figure 1 is a perspective view of the display molding unit for store fixtures or the like embodying my new design, a portion being broken away to indicate indefinite length;

The broken line representations in the drawings are for illustrative purposes only.

I claim:

The ornamental design for a display molding unit for store fixtures or the like, as shown and described.
